Patented Oct. 29, 1963

196,723

VALVE UNIT FOR GLASS TUBING

Roy Forrest Davis, Jr., 818 E. 22nd St. Court,
Des Moines, Iowa

Filed May 3, 1962, Ser. No. 69,960

Term of patent 14 years

(Cl. D16—1)

FIG. 1

FIG. 2

FIG. 3

FIG. 4

FIG. 5

FIG. 1 is a perspective view of a valve unit for glass tubing embodying my new design,

FIG. 2 is a perspective view taken from the opposite side of FIG. 1,

FIG. 3 is a side elevational view thereof,

FIG. 4 is an end view thereof, and

FIG. 5 is a cross sectional view taken on the line 5—5 of FIG. 3 with portions of two sections of glass tubing joined by a coupling for purposes of illustration only.

I claim:

The ornamental design for a valve unit for glass tubing, as shown and described.
